UNITED STATES PATENT OFFICE.

GEORGE N. MAS AND SOTIR K. LUBONIA, OF WASHINGTON, DISTRICT OF COLUMBIA.

DESIGN FOR A BOTTLE.

Application filed February 25, 1925. Serial No. 12,487. Term of patent 3½ years.

To all whom it may concern:

Be it known that we, GEORGE N. MAS and SOTIR K. LUBONIA, citizens of the United States, residing at the city of Washington, D. C., have invented a new, original, and ornamental Design for a Bottle, of which the following is a specification, reference being had to the accompanying drawing, forming part thereof.

We claim:

The ornamental design for a bottle as shown.

GEORGE N. MAS.
SOTIR K. LUBONIA.
